UNITED STATES PATENT OFFICE.

WILLIAM H. DE BUSK, OF CHICAGO, ILLINOIS, ASSIGNOR TO THE P. & M. COMPANY, OF CHICAGO, ILLINOIS, A CORPORATION OF ILLINOIS.

RAIL ANCHOR.

Application filed August 7, 1925. Serial No. 43,732.

This invention relates to rail anchors of the type illustrated in my application, Serial No. 749,984, filed November 14, 1924, of which the present application is a continuation in part. This type of anchor is adapted to grip a rail and by contact with a cross tie or other fixed portion of a track to hold the rail from longitudinal movement. It is one of the objects of my invention to provide a new and improved form and arrangement of parts in an anchor of this type by which an improved gripping effect will be attained by the use of a plurality of gripping members adapted by cooperation to grip a rail, the engagement of one of such members with the other member serving to hold both members in turned position about the longitudinal axis of the rail for effecting the desired grip upon the rail. It is another object of my invention to provide a construction of this type in which the gripping members are directly opposite each other transversely of the rail whereby each of said members is adapted to engage the cross tie. It is still another object of my invention to improve devices of this type in sundry details hereinafter pointed out. The preferred means by which I have accomplished my several objects are illustrated in the drawing and are herein-after specifically described. That which I believe to be new and desire to cover by this application is set forth in the claims.

In the drawing:

Fig. 1 is a face view of the preferred form of my invention in position upon a rail which is shown in vertical cross section.

Fig. 2 is a top plan view of the parts shown in Fig. 1.

Fig. 3 is a view similar to Fig. 1, but showing a modified form of construction.

Fig. 4 is a vertical cross section taken on line 4—4 of Fig. 3; and

Fig. 5 is another view similar to Fig. 1, but showing still another modified form of construction.

Referring particularly to Figs. 1 and 2, in which corresponding parts are indicated by the same reference characters,—10 indicates a rail, partly broken away, and mounted upon a cross tie 11. A jaw member comprising a body 12 is mounted upon the flange at one side of the rail, such member being provided with an arm 13 extending from the edge thereof across beneath the

rail into engagement with a turned portion 14 formed upon the body 15 of a jaw member mounted upon the flange of the rail at the opposite side. As will be noted by a reference to Fig. 1, the jaw member at the left comprises a bearing 16 upon the upper face of the flange at a point fairly close to the outer edge of the flange, while the bearing 17 upon the bottom face of the rail is located at a point considerably farther removed from the edge of the flange, whereby the jaw member is caused to have a shackle grip upon the flange when force is applied to the jaw member for turning it in counter clockwise direction in said Fig. 1. The jaw member at the right in said Fig. 1, however, is just the reverse of that described, the bearing 18 upon the bottom face of the flange being located fairly close to the edge of the flange, while the bearing 19 upon the upper face of the flange is located at a point farther removed from the edge of the flange. It is thus clear that when the jaw member at the right in said Fig. 1 is turned about the longitudinal axis of the rail in counter clockwise direction, it also is caused to have a shackle grip upon the flange. The proportions and arrangement of the members are such that when the members are placed in position upon the rail in engagement as shown in Fig. 1, the arm 13 presses downwardly upon the turned portion 14 of the other member, and the turned portion 14 presses upwardly upon the arm 13 whereby there is a tendency to turn or twist each of the jaw members in counter clockwise direction for effecting the desired grip upon the flange of the rail.

In the application of the device to a rail, the jaw member 15 is preferably first placed loosely upon the flange at the right, and the member 12 is placed in engagement with the other flange of the rail, with the extremity of the arm 13 engaging the notch in the turned portion 14 of the member 15. The arrangement is such that the member 12 may be then forced transversely of the rail toward the right in said figure. During this movement of the member 12, the diagonally disposed bottom face of the arm 13 engages the end portion 14 of the member 15 and forces the arm 13 upwardly with respect to the body 15, the arrangement being such that both jaw members are tightened upon the flange and the parts are necessarily dis-

torted for effecting the application of the device to a rail of the type for which the anchor is designed. At the end of the operation of applying the anchor by the movement of the body member 12 toward the right in Fig. 1 as just described, the shoulder 20 of the arm 13 is brought into snap engagement with the face of the turned portion 14 whereby it is adapted normally to hold the two members in operative engagement upon the flange of the rail.

In Figs. 3 and 4, I have provided a modified form of construction comprising two members adapted when the anchor is applied to a rail to snap by their resilience into operative holding position on the rail, in the construction shown in Fig. 3 the two members being initially engaged with each other and having the snap engagement with the edge of the rail, as compared with the construction shown in Fig. 1 in which the two members have snap engagement with each other. In both constructions, a bearing is provided on the bottom face of the flange at one side of the rail, and a bearing on the top face of the flange at the same side of the rail at a point in laterally spaced relation with respect to said bottom bearing and at a greater distance from the edge of the flange than that of said bottom bearing.

In the construction shown in Figs. 3 and 4, a clip 21 is provided, made from a heavy bar of metal bent into shape to provide a bearing at 22 upon the upper face of the flange at a considerable distance from the outer edge thereof, and a bearing 23 upon the bottom face of the flange at or near the side edge of the flange. A cooperating member preferably formed of heavy sheet metal is provided, having a body portion 24, with lugs or arms 25 and 26 extending from one face of the body 24 in position to engage respectively the bottom and top faces of the lower arm of the clip 21, the end portion of the lower arm of the clip being offset downwardly in such a manner as to provide in effect shoulders against which the edges of the lugs 25 and 26 engage. At its opposite end portion the body 24 is provided with an arm 27, which in turn is provided with an upward extension 28 at its end portion. The proportions and arrangement of the parts are such that normally the bearing 22 lies closer to the plane of the bearing 23 and the bearing adjacent to the upward projection 28 than is permitted when the device is in position upon a rail, it being necessary to distort the parts slightly for application of the device to the rail for forcing the bearing 22 upwardly from the plane of the bottom face of the rail. By this construction, the device is caused, as will be hereinafter pointed out, to have snap engagement with the rail when the device as a whole is driven from one side of the rail into engagement

therewith, and the device is caused to have a very firm operative grip upon the flange even after the slight loosening brought about by the snap engagement of the upward projection 28 with the edge of the flange.

In applying the device to a rail the clip 21 and the member 27 are engaged with each other, as shown in Fig. 3. The clip is then hooked over one flange of the rail base. In the latter position the projection 28 of the member 27 bears against the bottom surface of the rail base with sufficient pressure to hold the parts of the anchor in operative engagement with each other. The clip and member 27 are then driven transversely of the rail until the projection 28 snaps over the opposite edge of the rail base. As the bearing 22 of the clip is forced upon the inclined surface of the rail base, it tends to turn the clip counter clockwise in Fig. 3, which tendency is resisted by the engagement of the end 28 of the member 27 with the bottom of the rail base, whereby said members exert vertical pressure upon each other in opposite directions at the points of engagement of said members.

The construction illustrated in Fig. 5 is similar to that shown in Fig. 3, except that a shorter clip 29 is substituted for the clip 21; that the bearing upon the bottom face of the rail at one side thereof is effected through the medium of the lug 30 corresponding to the lug 26 of the construction shown in Fig. 3; and that the lug 31 corresponding with the lug 25 of the construction shown in Fig. 3 is diagonally disposed so as to engage the clip 29 at a different point thereon. It will be understood however that the construction and arrangement as illustrated in Fig. 5 are substantially the same in effect as the construction and arrangement as above described in connection with Figs. 3 and 4, the anchor is applied to the rail in substantially the same manner as the form shown in Fig. 3. In both cases, the resilient strength of the anchor which is materially distorted by the application of the anchor to the rail causes the anchor to have a very strong operative grip upon the flange of the rail such as to enable the anchor by contact with the tie 11 to hold the rail against longitudinal movement.

While I prefer to employ the constructions illustrated in my drawings, it will be understood that I do not desire to limit myself to the precise details except so far as the same are hereinafter specifically claimed, inasmuch as it is evident that changes might be made in the detailed form without departing from the spirit of my invention.

I claim:

1. A rail anchor comprising a jaw member adapted to have gripping engagement with the flange of a rail, and a second jaw member adapted to have gripping engage-

ment with the flange of the rail at the opposite side thereof, said members being adapted by vertical pressure upon each other in opposite directions at a point between the points where the jaw members engage the flange to hold each other in turned positions about axes extending longitudinally of the rail and adapted thereby to hold each other in operative engagement with the rail.

2. A rail anchor comprising a jaw member adapted to have gripping engagement with the flange of a rail, and a second jaw member adapted to have gripping engagement with the flange of the rail at the opposite side thereof, one of said members comprising an arm extending from its inner edge and engaging said other member at its inner edge portion for holding said members turned into operative gripping engagement with the flange.

3. A rail anchor comprising two jaw members adapted to be driven from opposite sides of the rail into position on the flange of the rail, said members being adapted by interengagement to swing each other in the same direction about axes extending longitudinally of the rail as they are driven into position and adapted thereby to cause each other to have operative gripping engagement with the flange.

4. A rail anchor comprising a jaw member adapted to have gripping engagement with the flange of a rail, and a second jaw member adapted to have gripping engagement with the flange of the rail at the opposite side thereof, said members being adapted by vertical pressure upon each other in opposite directions at a point between the points where the jaw members engage the flange to hold each other in turned positions about axes extending longitudinally of the rail and adapted thereby to hold each other in operative engagement with the rail, said members comprising parts adapted to have snap engagement with each other for holding the members from withdrawal from the rail.

5. A rail anchor comprising a jaw member adapted to have gripping engagement with the flange of a rail, and a second jaw member adapted to have gripping engagement with the flange of the rail at the opposite side thereof, one of said members comprising an arm extending from its inner edge and engaging said other member at its inner edge portion for holding said members turned into operative gripping engagement with the flange, and said arm being provided with a shoulder adapted to have snap engagement with the other member for holding the member from withdrawal from the rail, said arm being normally spaced from the bottom of the rail for permitting the necessary clearance for such snap engagement.

6. A rail anchor comprising two jaw

members adapted to be driven from opposite sides of the rail into position on the flange of the rail, said members being adapted by interengagement to swing each other in the same direction about axes extending longitudinally of the rail as they are driven into position and adapted thereby to cause each other to have operative gripping engagement with the flange, said members comprising parts adapted to have snap engagement with each other for holding the members from withdrawal from the rail.

7. A rail anchor comprising two separately formed members held by engagement with each other in position on the flange of a rail and bearing on said flange at a plurality of points, including a bearing on the bottom face of the flange at one side of the rail and a bearing on the top face of the flange at the same side of the rail at a point in laterally spaced relation with respect to said bottom bearing and at a greater distance from the edge of the flange than that of said bottom bearing, each member being adapted by pressure vertically upon the other member to hold such other member in turned position about an axis extending longitudinally of the rail whereby said two bearings have a strong shackle grip upon the rail.

8. A rail anchor comprising two separately formed members held by engagement with each other in position on the flange of a rail and bearing on said flange at a plurality of points, including a bearing on the bottom face of the flange at one side of the rail and a bearing on the top face of the flange at the same side of the rail at a point in laterally spaced relation with respect to said bottom bearing and at a greater distance from the edge of the flange than that of said bottom bearing, each member being adapted by pressure vertically upon the other member to hold such other member in turned position about an axis extending longitudinally of the rail whereby said two bearings have a strong shackle grip upon the rail, said two members being adapted when the anchor is applied to the rail to snap by their resilience into operative holding position on the rail.

9. A rail anchor comprising a member having a bearing on the top face of the flange of a rail, and a second member bearing on the bottom face of said rail and adapted by engagement with said first named member to apply pressure thereon tending to swing the upper end portion of said first named member toward the middle of the rail, said members comprising a second bearing on the bottom face of a rail adapted by cooperation with the first named bearing to effect a shackle hold on said flange.

10. A rail anchor comprising a member having a bearing on the top face of the flange of a rail at one side thereof in spaced relation to the edge of the flange, and a second member bearing on the bottom face of the rail at the opposite side and adapted by engagement with the first named member to apply pressure thereon tending to swing the upper end portion of said first named member toward the middle of the rail, said members comprising a second bearing on the bottom face of the rail at the same side thereof as said top bearing, said second bottom bearing being located closer to the edge of the flange than is said top bearing, said second bottom bearing and said top bearing being adapted to have a shackle hold on said flange.
11. A rail anchor comprising a member having spaced jaws adapted to embrace the flange at one side of a rail, and a separately formed member adapted by engagement with the first named member to hold said first named member in turned position about an axis extending longitudinally of the rail for applying upward pressure on the bottom face of the flange and applying

downward pressure on the top face of the flange at a point farther from the edge of the flange than the point at which the upward pressure is applied.

12. A rail anchor comprising a member having spaced jaws adapted to embrace the flange at one side of a rail, and a separately formed member adapted to engage with the bottom of the rail and with the first named member, whereby said members are interlocked with each other and when driven transversely of the rail exert vertical pressure upon each other to effect the grip of said device on the rail.

13. A rail anchor comprising a member having spaced jaws adapted to embrace the flange at one side of the rail, and a separately formed member adapted to engage with the bottom of the rail and with one of said spaced jaws at a point beneath said rail base, whereby said members are interlocked and when driven transversely of the rail exert pressure upon each other to effect a grip of said first mentioned member on the rail.

WILLIAM H. DE BUSK.
